SUCTION CLEANER NOZZLE WITH ROCKING LEVER TYPE ADJUSTABLE BRUSH

Willard H. McQuilkin, Canton, Ohio, assignor to The Hoover Company, North Canton, Ohio, a corporation of Ohio

Application April 25, 1947, Serial No. 743,781

2 Claims. (Cl. 15—373)

1

The present invention relates to cleaning tools of the type which are used with suction cleaning apparatuses and more particularly to a surface cleaning tool embodying a suction nozzle, a surface cleaning brush and a construction adjustably mounting the brush on the cleaning tool.

It is a principal object of the present invention to provide a surface cleaning tool for suction cleaning apparatuses embodying a brush construction which is advanced or retracted at the will of the operator by the application of a slight foot applied pressure to a projecting adjusting lever.

It is a further object of the present invention to provide a surface cleaning tool for suction cleaning apparatuses embodying a surface cleaning brush and adjusting mechanism all of which are retained in adjusted position and are retained in the nozzle structure by the brush mounting structure.

It is a further object of the present invention to provide a surface cleaning tool of the above described character in which the adjusting mechanism for the brush, the brush and the common mounting means are all assembled from the bottom of the nozzle casting.

Other objects and advantages of the invention will be apparent from the following specification and drawings, wherein:

Figure 1 is a front view, partly in section, of a cleaning tool having an adjustable brush shown in its lowered position for picking up litter;

Figure 2 is a vertical sectional view, partly in section, taken along line 2—2 of Figure 4 looking in the direction of the arrows illustrating the brush in lowered position;

Figure 3 is a vertical sectional view, partly in section, corresponding to Figure 2 but with the brush in raised position; and

Figure 4 is a vertical sectional view taken along line 4—4 of Figure 1, looking in the direction of the arrows.

The embodiment of the invention herein disclosed comprises a cleaning tool having a body consisting of an upper portion 10 and a lower portion 11. The cleaning tool body may be die cast of a suitable metal such as aluminum or it may be molded from a suitable metal or plastic as desired. The upper portion 10 of the cleaning tool includes a top wall 12, a front wall 13 and a pair of spaced walls 14 and 15 extending parallel to and in spaced relation to the wall 13 which cooperate with the sloping inner face 31 of the top wall 12 and end wall 16 to define a suction cleaning nozzle air passageway 30. The front wall 13 and wall 14 cooperate with end walls 17 and 18 and top wall 12 to define an open bottomed brush housing 19 in which a retractable brush 20 is adjustably mounted.

The rear wall 15 of the nozzle is formed with a

2

nozzle outlet opening 21 communicating with the air passageway 20 and a rearwardly projecting tubular socket 22. A hollow elbow 23 is rotatably mounted in the socket 22. The elbow 23 is adapted to be connected in a known manner to a suitable source of suction by means of a flexible hose and a manipulating wand. The elbow 23 is rotatably mounted in the socket 22 by a resilient annular spring wire 24 mounted in complementally formed grooves 25 in the socket 22 and the elbow 23.

The lower portion 11 of the body has a front lip 26 and a rear lip 27 merging at their opposite ends into end lips 28—28. The surfaces of the end lips 28—28 and the end portions 29 of the front and rear nozzle lips form supporting surfaces or shoes which lie in a plane lower than the intermediate portions of the front and rear lips. The rear lip 27 slopes upwardly and rearwardly while the end lip structures 28—29 are convex to allow the body 10 to be inclined during cleaning operations.

A furniture guard 32 of rubber or other suitable material extends along the front wall, the ends of the top wall, and the rear wall of the cleaning tool body. The furniture guard is provided with a plurality of spaced lugs, Figure 1, extending into marginal slots formed in the lower edges of the wall of the body portion 10. The front wall 13 and a flange 33 of the lower nozzle body 11 abut complementally formed lugs, not shown, on the furniture guard 32 to secure the same in position.

The end walls 17 and 18 of the brush housing 19 are provided with shoulders 34 against which complementally formed shoulders 36 on the brush back engage in the raised or retracted position on the brush. The brush 20 is formed of spaced tufts of bristles 37 mounted in the brush back 35 and secured thereto in a conventional manner. The end shoulders 36 of the brush back 35 are provided with suitable openings which slidably receive securing studs 38 threaded into the shoulders 34 on the nozzle body. Compression springs 39 surround the studs 38 between the stud heads and the shoulders 36 to urge the brush into the retracted position illustrated in Figure 3.

The novel adjusting mechanism for the brush 20 comprises an operating lever 40 best shown in Figures 2 to 4. The lever 40 includes a pair of angularly related operating arms 43 and 49 extending through slots 46 and 47, respectively, in the top wall of the brush housing 19. A cam surface 41 having a V-shaped central depression is positioned between the actuating arms 43 and 49. The cam surface 41 engages a V-shaped cam 42 depending from the top wall of the housing 19. The lever 40 is provided with a depending central portion having an open-ended slot 44 seated on a pintle 43 carried by upstanding lugs 45 on the brush back 35. The slots 46 and 47 and the

lugs 45 engage opposite sides of the lever 40 to prevent displacement thereof in the direction of the axis of the pintle 43. Angular displacement of the lever 40 is limited by engagement between the ends of the slots 46 and 47 and the arms 48 and 49, respectively. The biasing springs 39 constantly urge the brush 20 and the lever 40 upwardly to maintain firm engagement between the slot 44 and the pintle 43 and between the cam surfaces 41 and 42.

It is apparent from the foregoing that the springs 39 serve to retain the operating lever 40 in any of its adjusted positions and in operative relation to the brush structure and to the cam formed integrally with the nozzle body. The springs 39 and the studs 38 form the sole means for securing these parts to the nozzle body, in operative relation to each other and to retain the same in any adjusted position wherefor the springs perform a multiplicity of functions. The present construction provides a means by which the entire brush assembly and its adjusting mechanism may be applied to the nozzle from the bottom and which requires no machining of the nozzle body structure for the purpose of securing or mounting the adjusting mechanism per se. It is only necessary to provide suitable tapped holes for receiving the two studs 38 which form the only means for retaining the parts in assembled relation with the nozzle body.

In the operation of the device, the operator applies a slight pressure, preferably by foot, to whichever of the levers 48 and 49 is in its upper central position. If the parts are in the position illustrated in Figure 3, a foot pressure applied to the arm 49 will rock the lever in a clockwise direction disengaging the V-shaped notch in the cam surface 41 from the cam 42 and setting the parts in the position illustrated in Figure 2 which serves to project the brush structure against the force of the compression springs 39. If the brush is in its extended position, as shown in Figure 2, a slight pressure applied to the arm 48 will rock the lever 40 counter-clockwise and restore the parts to the position illustrated in Figure 3. Hence the brush is raised and lowered by a simple application of a downwardly applied foot pressure to the actuating lever therefor.

The elbow 23 is connected through a suitable hose to a source of suction causing a lowered pressure within the passage 38 which causes air to rush into that passage under the nozzle structure and entrain dirt and litter therewith. If the brush is in the retracted position illustrated in Figure 3, the tool operates as a straight suction cleaning tool in a well-known manner. If the operator depresses the lever 49 and lowers the brush to the position illustrated in Figure 2, the surface undergoing cleaning is subjected to a brushing action as the nozzle is moved back and forth thereacross which aids in dislodging and picking up embedded dirt and litter.

The present construction provides a suction cleaning tool nozzle embodying a brush which is adjustable by a mechanism consisting essentially of a single lever which is not rigidly and permanently attached either to the nozzle body or to the brush structure and is always operated by downwardly applied foot pressure. No machining of the nozzle is required to mount or seat the

adjusting lever mechanism. The foregoing greatly reduces the manufacturing and assembling costs of the apparatus and results in a very simple, effective and reliable construction.

What is claimed is:

1. A surface cleaning tool comprising a body member having walls defining an air passageway terminating in surface engaging lips forming a suction nozzle and a brush housing contiguous to said air passageway and opening downwardly, a brush, means mounting said brush in said housing for slidable movement between a projected surface engaging position and a retracted inoperative position, a control member, means forming a separable rocking connection between said control member and the top of said brush, coacting cam surfaces on said control member and said housing shaped to cause said brush to project and retract as said control member is rocked on said connection, actuating means on said control member extending through an opening in a wall of said housing and being insertable and withdrawable through said opening from said brush housing when the apparatus is assembled or disassembled, means biasing said brush upwardly in said housing to maintain said connection in assembled relation and said cam surfaces in engagement and said actuating means extended through said opening in the wall of said housing.
- 10 2. A surface cleaning tool comprising a body member having walls defining an air passageway terminating in surface engaging lips forming a suction nozzle and a brush housing contiguous to said air passageway and opening downwardly, a brush, means mounting said brush in said housing for slidable movement between a projected surface engaging position and a retracted inoperative position, a control member, means forming a separable rocking connection between said control member and the top of said brush, coacting cam surfaces on said control member and said housing shaped to cause said brush to project and retract as said control member is rocked on said connection, actuating means on said control member extending through an opening in a wall of said housing and being insertable and withdrawable through said opening from said brush housing when the apparatus is assembled or disassembled, means biasing said brush upwardly in said housing to maintain said connection in assembled relation and said cam surfaces in engagement and said actuating means extended through said opening in the wall of said housing.
- 15 3. A surface cleaning tool comprising a body member having walls defining an air passageway terminating in surface engaging lips forming a suction nozzle and a brush housing contiguous to said air passageway and opening downwardly, a brush, means mounting said brush in said housing for slidable movement between a projected surface engaging position and a retracted inoperative position, a control member, means forming a separable rocking connection between said control member and the top of said brush, coacting cam surfaces on said control member and said housing shaped to cause said brush to project and retract as said control member is rocked on said connection, actuating means on said control member extending through an opening in a wall of said housing and being insertable and withdrawable through said opening from said brush housing when the apparatus is assembled or disassembled, means biasing said brush upwardly in said housing to maintain said connection in assembled relation and said cam surfaces in engagement and said actuating means extended through said opening in the wall of said housing.
- 20 4. A surface cleaning tool comprising a body member having walls defining an air passageway terminating in surface engaging lips forming a suction nozzle and a brush housing contiguous to said air passageway and opening downwardly, a brush, means mounting said brush in said housing for slidable movement between a projected surface engaging position and a retracted inoperative position, a control member, means forming a separable rocking connection between said control member and the top of said brush, coacting cam surfaces on said control member and said housing shaped to cause said brush to project and retract as said control member is rocked on said connection, actuating means on said control member extending through an opening in a wall of said housing and being insertable and withdrawable through said opening from said brush housing when the apparatus is assembled or disassembled, means biasing said brush upwardly in said housing to maintain said connection in assembled relation and said cam surfaces in engagement and said actuating means extended through said opening in the wall of said housing.
- 25 5. A surface cleaning tool comprising a body member having walls defining an air passageway terminating in surface engaging lips forming a suction nozzle and a brush housing contiguous to said air passageway and opening downwardly, a brush, means mounting said brush in said housing for slidable movement between a projected surface engaging position and a retracted inoperative position, a control member, means forming a separable rocking connection between said control member and the top of said brush, coacting cam surfaces on said control member and said housing shaped to cause said brush to project and retract as said control member is rocked on said connection, actuating means on said control member extending through an opening in a wall of said housing and being insertable and withdrawable through said opening from said brush housing when the apparatus is assembled or disassembled, means biasing said brush upwardly in said housing to maintain said connection in assembled relation and said cam surfaces in engagement and said actuating means extended through said opening in the wall of said housing.
- 30 6. A surface cleaning tool comprising a body member having walls defining an air passageway terminating in surface engaging lips forming a suction nozzle and a brush housing contiguous to said air passageway and opening downwardly, a brush, means mounting said brush in said housing for slidable movement between a projected surface engaging position and a retracted inoperative position, a control member, means forming a separable rocking connection between said control member and the top of said brush, coacting cam surfaces on said control member and said housing shaped to cause said brush to project and retract as said control member is rocked on said connection, actuating means on said control member extending through an opening in a wall of said housing and being insertable and withdrawable through said opening from said brush housing when the apparatus is assembled or disassembled, means biasing said brush upwardly in said housing to maintain said connection in assembled relation and said cam surfaces in engagement and said actuating means extended through said opening in the wall of said housing.
- 35 7. A surface cleaning tool comprising a body member having walls defining an air passageway terminating in surface engaging lips forming a suction nozzle and a brush housing contiguous to said air passageway and opening downwardly, a brush, means mounting said brush in said housing for slidable movement between a projected surface engaging position and a retracted inoperative position, a control member, means forming a separable rocking connection between said control member and the top of said brush, coacting cam surfaces on said control member and said housing shaped to cause said brush to project and retract as said control member is rocked on said connection, actuating means on said control member extending through an opening in a wall of said housing and being insertable and withdrawable through said opening from said brush housing when the apparatus is assembled or disassembled, means biasing said brush upwardly in said housing to maintain said connection in assembled relation and said cam surfaces in engagement and said actuating means extended through said opening in the wall of said housing.
- 40 8. A surface cleaning tool comprising a body member having walls defining an air passageway terminating in surface engaging lips forming a suction nozzle and a brush housing contiguous to said air passageway and opening downwardly, a brush, means mounting said brush in said housing for slidable movement between a projected surface engaging position and a retracted inoperative position, a control member, means forming a separable rocking connection between said control member and the top of said brush, coacting cam surfaces on said control member and said housing shaped to cause said brush to project and retract as said control member is rocked on said connection, actuating means on said control member extending through an opening in a wall of said housing and being insertable and withdrawable through said opening from said brush housing when the apparatus is assembled or disassembled, means biasing said brush upwardly in said housing to maintain said connection in assembled relation and said cam surfaces in engagement and said actuating means extended through said opening in the wall of said housing.
- 45 9. A surface cleaning tool comprising a body member having walls defining an air passageway terminating in surface engaging lips forming a suction nozzle and a brush housing contiguous to said air passageway and opening downwardly, a brush, means mounting said brush in said housing for slidable movement between a projected surface engaging position and a retracted inoperative position, a control member, means forming a separable rocking connection between said control member and the top of said brush, coacting cam surfaces on said control member and said housing shaped to cause said brush to project and retract as said control member is rocked on said connection, actuating means on said control member extending through an opening in a wall of said housing and being insertable and withdrawable through said opening from said brush housing when the apparatus is assembled or disassembled, means biasing said brush upwardly in said housing to maintain said connection in assembled relation and said cam surfaces in engagement and said actuating means extended through said opening in the wall of said housing.
- 50 10. A surface cleaning tool comprising a body member having walls defining an air passageway terminating in surface engaging lips forming a suction nozzle and a brush housing contiguous to said air passageway and opening downwardly, a brush, means mounting said brush in said housing for slidable movement between a projected surface engaging position and a retracted inoperative position, a control member, means forming a separable rocking connection between said control member and the top of said brush, coacting cam surfaces on said control member and said housing shaped to cause said brush to project and retract as said control member is rocked on said connection, actuating means on said control member extending through an opening in a wall of said housing and being insertable and withdrawable through said opening from said brush housing when the apparatus is assembled or disassembled, means biasing said brush upwardly in said housing to maintain said connection in assembled relation and said cam surfaces in engagement and said actuating means extended through said opening in the wall of said housing.
- 55 11. A surface cleaning tool comprising a body member having walls defining an air passageway terminating in surface engaging lips forming a suction nozzle and a brush housing contiguous to said air passageway and opening downwardly, a brush, means mounting said brush in said housing for slidable movement between a projected surface engaging position and a retracted inoperative position, a control member, means forming a separable rocking connection between said control member and the top of said brush, coacting cam surfaces on said control member and said housing shaped to cause said brush to project and retract as said control member is rocked on said connection, actuating means on said control member extending through an opening in a wall of said housing and being insertable and withdrawable through said opening from said brush housing when the apparatus is assembled or disassembled, means biasing said brush upwardly in said housing to maintain said connection in assembled relation and said cam surfaces in engagement and said actuating means extended through said opening in the wall of said housing.
